(57) **CLAIM**

The ornamental design for a hunting blind, as shown and described.

DESCRIPTION

FIG. 1 is a front, right and top perspective view of a hunting blind, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is another front, right and top perspective view of the hunting blind, wherein the three pieces of the hunting blind and the other two pieces of the hunting blind are separated from each other.

FIG. 12 is a front and top perspective view of the hunting blind in a usable state, wherein the five pieces of the hunting blind are enclosed.

FIG. 13 is another front and top perspective view of the hunting blind, wherein the two pieces of the hunting blind connect with the three pieces of the hunting blind in another way; and,

FIG. 14 is another front, and top perspective view of the hunting blind in a usable state, wherein the four pieces of the hunting blind are enclosed and one piece of the hunting blind connects the four pieces on the top.

The broken lines depict portions of the hunting blind that form no part of the claimed design. The dot-dash broken lines in FIGS. 1, 2, 9, and 10 depict the boundaries of the enlargements that form no part of the claimed design.
